UNITED STATES PATENT OFFICE.

ROY L. KAY, OF CALIFORNIA, MISSOURI.

SAFETY-ENVELOP.

1,194,630.

Specification of Letters Patent. Patented Aug. 15, 1916.

Application filed April 14, 1916. Serial No. 91,115.

To all whom it may concern:

Be it known that I, ROY L. KAY, a citizen of the United States, residing at California, in the county of Moniteau and State of Missouri, have invented certain new and useful Improvements in Safety-Envelops; and I do hereby declare the following to be a full, clear, and exact description of the invention, such as will enable others skilled in the art to which it appertains to make and use the same.

The invention relates to improvements in safety envelopes.

The object of the present invention is to improve the construction of safety envelopes and to provide a simple, practical and efficient construction which will require no more material than an ordinary envelop and capable of coöperation with the usual gummed areas of the envelop to securely seal the same whereby the envelop after being sealed prevents any surreptitious opening of the same without clearly indicating the fact that the envelop has been tampered with.

With these and other objects in view, the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

In the drawing Figure 1 is an elevation of an envelop constructed in accordance with this invention, the top or main sealing flap being open, Fig. 2 is a similar view the envelop being sealed, Fig. 3 is a detail sectional view on the line 3—3 of Fig. 2, Fig. 4 is a detail rear elevation illustrating another arrangement of the central tongue, Fig. 5 is a similar view taken from the interior of the envelop.

Like numerals of reference designate corresponding parts in the several figures of the drawing.

In the accompanying drawing in which is illustrated the preferred embodiment of the invention, the safety envelop comprises a body portion 1, a bottom flap 2, end flaps 3 and a top or main sealing flap 4. The top flap which has a gummed area 5 for sealing the envelop in the usual manner is provided

with a centrally arranged opening 6 preferably of segmental form and adapted when the top flap 4 is folded over the bottom and end flaps 2 and 3 as illustrated in Fig. 2 of 60 the drawing to have a tongue 7 passed through it and folded backwardly or inwardly and sealed against the adjacent portion of the bottom flap 2 as clearly illustrated in Fig. 3 of the drawing. The tongue 65 7 which is provided at its outer end with a gummed area 7 is substantially oblong and it is cut from the bottom flap 2 and is connected at its inner end with the same and is arranged at its side edges and outer end in 70 spaced relation with the edges of the opening 9 formed by cutting the material to provide the tongue 7. The tongue 7 is further weakened by a longitudinal slot 10 extending outwardly from the inner end of the 75 tongue and terminating short of the gummed area 8 and adapted to cause a ready separation of the tongue from the bottom flap at the inner end of the tongue should an attempt be made to steam the envelop open or 80 unseal the tongue by forcing an instrument beneath the gummed portion of the same. The tongue will effectually prevent the main sealing flap or top flap 4 from being raised or separated from the bottom flap 2. 85

In order to detect any opening of the end flaps, each of the end flaps is provided at the upper portion adjacent to the side edges of the bottom flap with inner and outer interfitting tongues 11 and 12 provided with 90 laterally reduced terminal portions 13 and 14 arranged side by side and spaced apart by an intervening slot 15 of angular formation. The tongues are spaced apart at their side edges from the adjacent portion of the 95 end flap by side slots 16 which are preferably arranged in parallelism and disposed at an angle or inclination to enable the interfitting tongues to lie within the gummed area 5 of the main or top flap when the latter is closed and the envelop sealed as clearly illustrated by the dotted lines in Fig. 2 of the drawing. The interfitting tongues which will be torn should the envelop be opened at either end will clearly indicate the fact 100 that the opening of the envelop has been effected and as they lie beneath the gummed portion of the top flap they will be entirely concealed by the latter so that a person attempting to open the envelop will destroy 105 the tongues before he is aware of such safety sealing means. 110

The central sealing tongue 7 may as illustrated in Figs. 4 and 5 of the accompanying drawing be provided on its exterior with adhesive material and be secured to the inner face of the top flap. In this arrangement the tongue will be held in a partially concealed condition between the top and bottom flaps at the overlapping gummed sealed portions of the same and the slotted portion of the tongue will be exposed at the opening 6.

What is claimed is:—

1. A safety envelop including a body and top and bottom flaps, the top flap being arranged to overlap the bottom flap and having an opening and the bottom flap being provided with an integral oblong tongue of substantially uniform width throughout its entire length cut from the bottom flap of material located entirely above the lower edge of the bottom flap when the latter is folded, said tongue having its side and end edges arranged in spaced relation with the edges of the opening formed by the cutting of the flap, said tongue being provided at its inner portion with a longitudinal slot and the outer portion of the tongue being provided with adhesive material, said tongue being passed through the opening of the top flap and sealed against the envelop by the said adhesive material.

2. A safety envelop including a body portion, a bottom flap, end flaps secured to the bottom flap and provided at their upper por-

tions with inner and outer interfitting sealing tongues having laterally reduced free terminal portions spaced from each other by an intervening slot and the side edges of the tongues being spaced from the adjacent portions of the end flaps by side slots and a top flap foldable over the bottom and end flaps and provided with an area having adhesive material adapted to cover and conceal the interfitting tongues of the end flaps.

3. A safety envelop including a body and top and bottom flaps, the top flap being arranged to overlap the bottom flap and having an integral oblong tongue of substantially uniform width throughout its entire length cut from the bottom flap of material located entirely above the lower edge of the bottom flap when the latter is folded, said tongue having its side and end edges arranged in spaced relation with the edges of the openings formed by the cutting of the flaps, said tongue being provided at its inner portion with a longitudinal slot located at the opening of the top flap and the outer portion of the tongue being provided with adhesive material for securing it to the envelop.

In testimony whereof I affix my signature in presence of two witnesses.

R. Y. L. KAY.
